UNITED STATES PATENT OFFICE

LOUIS FASULO, OF BROOKLYN, NEW YORK.

TAILORING IMPLEMENT SET

Application filed January 15, 1930. Serial No. 420,867.

This invention relates to new and useful improvements in a tailoring implement-set.

The invention has for an object the provision of a device of the class mentioned which is of simple durable construction, dependable in use and efficient in action, and which can be manufactured and sold at a reasonable cost.

The invention proposes a tailoring implement-set secured on a strap with an intermediate protuberance, and various needle-set objects attached magnetically thereon. This arrangement permits convenient carrying of various articles needed by an operator performing certain tailoring work, on one's wrist or waist line.

The invention also proposes that one of said needle-set objects be a pin cushion adapted to magnetically hold pins, needles, and the like. It should include a soft top member into which pins may be inserted and a magnetic screen beneath the top member for holding the pins.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a plan view of a device constructed according to this invention.

Fig. 2 is a side elevational view of Fig. 1.

Fig. 3 is an enlarged transverse sectional view taken on the line 3-3 of Fig. 1.

Fig. 4 is a fragmentary view, similar to Fig. 1, showing another modification.

Fig. 5 is a vertical sectional view of a pin cushion constructed according to a modified form of the invention.

Fig. 6 is a horizontal sectional view taken on the line 6-6 of Fig. 5.

Fig. 7 is a fragmentary sectional view taken on the line 7-7 of Fig. 6.

Fig. 8 is an enlarged detailed fragmentary view of a portion of Fig. 5.

The tailoring implement-set consists of a

5 tuberance 11, and various needle-set objects attached thereon. The said wrist strap is preferably made of leather and is provided with a buckle 12 at one end. This buckle consists of a rectangular frame 13 and a finger 14 pivotally mounted on said side of the frame. The end of the strap 10 is looped around the side of the frame provided with the finger 14 and is thus held by a rivet 15. A transverse strap 16 is arranged in a loop near the buckle for receiving the opposite end of the strap 10. The said opposite end of the strap is formed with a plurality of apertures 17 engageable by the finger 14 of the buckle for latching the strap upon one's wrist.

10 The said protuberance 11 is laterally arranged on the strap and within its plane. The needle objects referred to consist of a pin cushion 18 supporting pins 19, a magnetized clip bracket 20 for supporting a thimble 21, and a magnetized clip bracket 22 for supporting a needle 23. Rivets 24 are attached to these various objects and extend thru the strap accomplishing the attaching of the objects on the strap. An inner shield 25 is secured to the bottom of the strap in the vicinity of the rivets and extends over the rivets for shielding one's wrist against the rivet heads.

15 In Fig. 4, a magnetized clip 22' is provided to hold scissors 23' in position.

The said clip 20 for the thimble 21 consists of a base 26 supporting several magnetized vertical fingers 27 having out-turned top ends and also supporting one magnetized finger 28 having an inwardly directed top end for extending over the top edge of the thimble and securely holding it in place. The clip 22 for supporting the needle 23 consists of a substantially U-shaped magnetized plate member attached at its base upon the strap and its arms being capable of engaging the opposite sides of the needle for accomplishing the holding.

20 In operation, it is intended that the wrist needle-set be attached upon one's wrist during its use. Whenever the needle, thimble or the like is to be used, it may quickly be withdrawn from its magnetized holding clip. Pins as needed may be withdrawn from the

cushion and when not needed are inserted.

In Figs. 5 to 7 inclusive, the cushion is adapted to magnetically hold pins, needles, and the like. It consists of a container 30 for attachment upon the wrist strap 10 and opened at the top 31. A soft pad closing member 32 preferably of rubber, sponge or the like closes the top of the container and rests upon an internal ridge 33 secured within the container completely around its inner side. This pad member 32 is covered with covering sheet 32' of velvet or the like to improve the appearance of the pad. A magnetizable screen 34 is engaged within the container beneath the internal ridge 33 and is restrained against outward motion by its edges engaging against the ridge. Expansion springs 35 normally urge the screen 34 into engagement with the ridge. A permanent magnet 36 is attached within the container and serves to maintain the magnetism of the screen.

The screen 34 is preferably formed of iron wire mesh. The springs 35 are attached on one of their ends 37 and are free at their other ends so as to urge the screen upwards. The magnet 36 is a permanent bar magnet of conventional design and has a north pole 38 and a south pole 39. A means is provided for adjusting the position of the magnet so that pins engaged thru the pad covering 32' and the pad 32 may not wear out a certain portion of the pad, that is, assume the magnet at the center, pins must be so placed in the pad as to avoid the magnet. Later on, the magnet may be moved and the avoided area used for the reception of pins.

The means for adjusting the position of the magnet consists of a screw 40 rotatively mounted across the container 30 and threadedly engaged with the magnet 36. One end 41 of this screw is formed with a head reachable from the outside of the container as illustrated in Fig. 8 so that it may be manually rotated for feeding the magnet one way or the other way. Pins engaged in the pad 36 will be restrained from falling out in that their inner ends engage thru the mesh of the screen 34 and are then magnetically held. Even though the wearer of the wrist band exposes the pad to rough handling, the magnetic screen will prevent the falling out of the pins.

It is to be understood that my tailoring set is not limited to needles, pins, thimbles and scissors, but any other suitable implement may be retained in the magnetized clip which may be of suitable shape to hold the said implements.

It is also to be understood that the strap 10 may be of any desired size and material for keeping my tailoring implement-set on one's wrist, waist or wherever convenient.

While I have shown and described the preferred embodiment of my invention, it is to

be understood that I do not limit myself to the precise construction herein disclosed and the right is reserved to all changes and modifications coming within the scope of the invention as defined in the appended claims. 70

Having thus described my invention, what I claim as new, and desire to secure by United States Letters Patent is:—

1. A tailoring implement-set, including a strap with an intermediate protuberance, and a magnetized clip bracket attached thereon for supporting a thimble, said clip bracket for the thimble consisting of a base with several vertical fingers having out-turned top ends forming one polarity of the magnetized clip and one vertical finger with an inturned top end forming the other polarity of the said magnetized clip, said last finger capable of extending over the top edge of the thimble for holding it in place. 80 85

2. In a tailoring implement-set, a pin cushion, comprising a container for attachment on a wrist strap of the set and opened at the top, a soft pad and pad cover closing the top of the container, an internal ridge around the interior of the container beneath said pad, a screen engageable against the bottom of said ridge, expansion springs normally urging the screen against the ridge, and a permanent magnet within the container for magnetizing said screen. 90 95

3. In a tailoring implement-set, a pin cushion, comprising a container for attachment on a wrist strap of the set and opened at the top, a soft pad and pad cover closing the top of the container, an internal ridge around the interior of the container beneath said pad, a screen engageable against the bottom of said ridge, expansion springs normally urging the screen against the ridge, a permanent magnet within the container for magnetizing said screen, and means for adjusting the position of the magnet. 100 105

4. In a tailoring implement-set, a pin cushion, comprising a container for attachment on a wrist strap of the set and opened at the top, a soft pad and pad cover closing the top of the container, an internal ridge around the interior of the container beneath said pad, a screen engageable against the bottom of said ridge, expansion springs normally urging the screen against the ridge, a permanent magnet within the container for magnetizing said screen, and means for adjusting the position of the magnet, comprising a screw rotatively mounted across the container and threadedly engaging with the magnet, and means for manually rotating the screw for feeding the magnet one way or the other. 110 115

5. In a tailoring implement-set, a pin cushion, comprising a container for attachment on a wrist strap of the set and opened at the top, a soft pad and pad cover closing the top of the container, an internal ridge around the interior of the container beneath said pad, 120 125

a screen engageable against the bottom of said ridge, expansion springs normally urging the screen against the ridge, a permanent magnet within the container for magnetizing said screen, and means for adjusting the position of the magnet, comprising a screw rotatively mounted across the container and threadedly engaging with the magnet, and means for manually rotating the screw for feeding the magnet one way or the other, comprising a head formed at one end of the said screw and accessible from the outside of the container.

In testimony whereof I have affixed my
15 signature.

LOUIS FASULO.
